UNITED STATES PATENT OFFICE.

MARK L. LANDRUM, OF PLYMOUTH, CALIFORNIA.

AUTOMATICALLY-ADJUSTING GEAR PULLER.

Application filed August 24, 1926. Serial No. 131,193.

This invention relates to improvements for pulling gears and the like from their shafts, my principal object being to provide a device for the purpose, whose gear engaging arms simultaneously adjust themselves into or out of position when the tool is engaged with or removed from a gear by a single quickly accomplished hand operation, and without necessitating moving the center pulling screw.

A further object is to arrange the parts of the tool so that when a pulling pressure is exerted it will be impossible for the arms to slip from the gear, and the greater the pressure, the greater will be the tendency for the arms to grip the gear.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawings similar characters of reference indicate corresponding parts in the several views:

Fig. 1 is a sectional elevation of my improved gear puller.

Fig. 2 is a top plan view of the tool.

Referring now more particularly to the characters of reference on the drawings, the numeral 1 denotes a cupped disc having a central hub 2 projecting from the concave face of the disc. A pulling screw 3 is threaded through the hub, said screw having a square or similar shaped head 4 to enable a wrench to be applied.

Slidable on the hub 2 is a sleeve 5 formed with a hand grip portion 6 on its outer end, the screw projecting through and beyond said sleeve a certain distance.

Projecting radially from the sleeve are a plurality of spaced pairs of ears 7 which form bearings for the pins 8 of a corresponding number of arms 9. The arms project beyond the disc 1 a certain distance and at their outer ends (which are opposite to the headed end of the screw) are provided with inwardly projecting pads 10 to pass under and engage the side of a gear to be pulled.

The arms are formed with heavy lugs 11 which overhang and engage the concave face of the disc, and they also have guide fingers 12 engaging the opposite and convex face of

the disc, slots 13 being thus formed between the members 11 and 12.

The curvature and depth of these slots relative to the disc is such that the arms turning on the pins 8 may move inwardly toward each other until the pads 10 are fairly close together so as to engage a small gear; or they may swing outwardly until the ends of the members 11 and 12 are near the rim of the disc, as indicated in dotted lines in Fig. 1.

With this position of the arms of course a large gear may be engaged thereby. Further separating movement of the arms is prevented by the ends thereof above the pins 8 coming in contact with abutments 14 formed on the sleeve 5 between the bearing ears 7.

This movement takes place automatically when the sleeve 5 and disc 1 are moved to and from each other, since the center of curvature of the disc and slot 13 is on the central longitudinal axis of the sleeve and hub. As the disc and pivot points of the arms are moved to and from each other, the arms therefore must swing one way or the other so as to maintain the center of curvature of the slots 13 at the same point as the center of curvature of the disc 1.

The sleeve and disc are held from turning relative to each other by any suitable means, such as for instance a pair of lugs 15 on the disc between which the finger 12 of one of the arms 9 passes.

In operation the handle member 6 is grasped by one hand and the head of the screw 3 in the other. The arms are then separated by a relative movement between the parts to which these elements are connected, so as to enable the pads 10 to pass by the periphery of the gear 16 to be pulled. The movement of the hand engaged parts is then reversed until the pads 10 pass under and engage the face of the gear furthest from the tool. The screw 3 is then advanced by hand until it engages the end of the gear shaft 17, when a wrench is applied to the head 4 to further turn the screw and exert the necessary pulling pressure.

Such pressure of course causes the gear to be pulled from the shaft and also causes the arms by reason of the disc and the lugs 11 engaging the same, to tend to move even closer together, so that slipping of the arms from the gear is impossible.

It will be seen that all load is taken by

the disc and by the heavy arm lugs 11, which together with the arms are designed to have sufficient strength to take any strains which may be imposed thereon.

5 The fingers 12 do not come into play with the pulling operation and are simply provided to insure simultaneous separation of the arms when the tool is being withdrawn from the gear.

10 From the foregoing description it will be readily seen that I have produced such a device as substantially fulfills the objects of the invention as set forth herein.

15 While this specification sets forth in detail the present and preferred construction of the device, still in practice such deviations from such detail may be resorted to as do not form a departure from the spirit

of the invention, as defined by the appended claim.

Having thus described my invention what I claim as new and useful and desire to secure by Letters Patent is:

20 A gear puller comprising a screw for engagement with the end of a shaft, arms for engagement with a gear on the shaft, a cupped disc, a hub thereon through which the screw is threaded, a sleeve member 25 slideable on the hub, pivotal connections between the arms and sleeve member, and projections on the inner faces of the arms straddling the opposed faces of the disc and forming slots concentrically aligned with the disc.

25 In testimony whereof I affix my signature.

30 MARK L. LANDRUM.
